SEALING DEVICE FOR THE DOORS OF
COKE OVENS

Jean Charles Fourmanoit, Brussels, Belgium

Application August 14, 1948, Serial No. 44,286
In Belgium August 27, 1947

7 Claims. (Cl. 202—248)

1

My present invention relates to a sealing device for the doors of coke and like ovens based on the use of a sealing frame which is removable and articulated.

Devices of this kind are already known in which angle irons, carried by a very flexible sheet of metal and forming knife blades for contact with a guard plate of the door frame, are used as sealing elements.

Such devices involve various defects which may be summarized as follows:

1. These knife blades tend to fold over because of the lack of firm seating in the very flexible metallic sheet and of their lack of rigidity.

2. The flexible sheet and the asbestos lining thereof are very fragile (usually the metal sheet has a thickness of 1½ mm.) and often deteriorate, particularly when the door is cleaned.

3. The knife blade has a bearing width of only about 2 mm. It is not strong and has often to be repaired. Moreover it is essential that the same be cleaned, and this often results in damage thereto.

4. The construction of such a frame entails careful work in making the knife blade and in the riveting of the profiled members of the metal sheet.

In the present invention the sealing frame is furnished with a joining metallic seal having a rounded surface for contact with the guard plate of the door frame.

In carrying the invention into practical effect the sheet metal of the sealing frame to which the metallic seal is rigidly secured is a strong sheet or plate, for example, of 5 mm. thickness, without an asbestos lining.

The annexed drawings show, by way of example only, a manner in which the invention may be carried into effect in practice.

Fig. 1 is a horizontal sectional view illustrating the door, the fixed frame and the sealing means.

Figs. 2, 3, 4 and 5 are detail views illustrating different forms which the metallic seal may take.

In Fig. 1, of the accompanying drawings, 1 designates the body of the door which is provided, in known fashion, with a refractory covering 2 and which enters the opening of the chamber and 3 is the door frame with a guard plate 3.

As is usual, I provide a closure device and this, in the example illustrated, comprises bolts 4 which are engaged with bearing brackets 6 fixed to the frame 3 of the door.

Fluid-tightness between the door of the coke oven and the guard plate 3 is secured by means of a removable sealing frame 7 which in accordance with the invention has the feature of in-

cluding a jointing metallic seal 8 which has a rounded surface for contacting the guard plate and replacing the thin knife blade formations which are used in some known arrangements.

5 An important characteristic of the invention is in addition that the sheet 7, which is rigidly connected to the seal 8, for instance by welding, is preferably of robust sheet or plate, for example of a thickness of 5 mm. without a lining of asbestos.

At each side of the door, there is provided between the sheet or plate 7 and a projection 9 on the door side, a joint of asbestos or other suitable material comprising a simple cord 10, and 15 the assembly of parts 7, 8 and 10 is, in the example illustrated, applied to the door by clamps 11 and bolts 12. Brackets 13 which are rigidly secured to the door, support screws 14 which apply the joint 8 to the bearing face of the frame 20 and thus produce the sealing effect.

The clamps 11 and bolts 12 are uniformly distributed around the whole of the perimeter of the door.

A frame as described has the advantage of not 25 presenting a thin profile or a surface which is liable to deteriorate either as a result of temperature action or of the movements which it undergoes when in use in a hot and oxidising atmosphere, or by reason of the action of tools or appliances used to clean the door.

30 The seal 10 may be of any appropriate form and may be of various shapes at the part connected to the sheet or plate 7. Thus the contact surface of this seal may be an arc of a circle, be oval and so on, in section. Figs. 2, 3, 4 and 5 illustrate different forms which it may take, but it is to be understood that these forms are given by way of example only and are not exhaustive.

What is essential is the part 16 being of 40 rounded shape (see Fig. 2) since this ensures the formation on the metallic seal 8 of a deposit 17 of pitch or tar which opposes any passage of gas.

Once made, these deposits of pitch or tar do 45 not have to be removed and it is not necessary, at each discharge of the oven to clean the projecting ledge of the guard plate facing the frame.

Thus a permanent sealing is produced, so to 50 say, by the operation of the oven itself and in a manner which may be termed automatic.

The device described thus has considerable advantages of a constructional nature by reason of the rigidity and the simplicity of the frame 55 and of the absence of delicate manufacturing operation, and in addition it provides a great economy of labour in the course of its use.

What I claim is:

1. In combination with a coke oven door, a stationary metal door frame provided with an outer plane sealing surface surrounding the opening in said frame, a removable, transversely rigid, sealing frame, said removable frame being provided, on its side facing said sealing surface of said stationary door frame, with a jointing metallic seal having a half-rounded shape, means carried by the door and acting on the other side of said removable frame near the outer periphery thereof for applying said jointing metallic seal against said sealing surface of said stationary frame, a gasket of heat-resisting material between said rigid sealing frame and a surface of said door disposed parallel to the adjacent surface of the sealing frame, said gasket having a curved surface in contact with said adjacent surface of the sealing frame substantially along the inner peripheral edge of the latter, and clamping means acting on the opposite surface of said removable rigid sealing frame adjacent the inner periphery of the latter to apply said sealing frame and gasket against the door so as to form an articulated joint.

2. A combination as claimed in claim 1, in which said gasket has a substantially circular cross-section.

3. A combination as claimed in claim 1, in which said removable rigid sealing frame is formed of sheet iron plate having a thickness of about 5 mm.

4. In combination with a coke oven door, a stationary metal door frame provided with an outer plane sealing surface surrounding the opening in said frame, a removable, transversely rigid, sealing frame, said removable frame being provided, on its side facing said sealing surface of said stationary door frame, with a jointing metallic seal having a half rounded shape, brackets rigidly secured to the door, means carried by said brackets and acting on the other side of said removable frame near the outer periphery thereof for applying said jointing metallic seal against said sealing surface of said stationary frame, a gasket of heat-resisting material between said rigid removable sealing frame and a surface of said door disposed parallel to the adjacent surface of the sealing frame, said gasket having a curved surface in contact with said adjacent surface of the sealing frame substantially along the inner periphery of the latter, and clamping means carried by the door and including edge portions acting on the opposite surface of said removable frame adjacent the inner periphery of the latter to apply said sealing frame and gasket against the door.

5. In combination with a coke oven door, a stationary metal door frame provided with an outer plane sealing surface surrounding the opening in said frame, a removable, transversely rigid, sealing frame, said removable frame being provided, on its side facing said sealing surface of said stationary door frame, with a jointing metallic seal having a half rounded shape, brackets rigidly secured to the door, means carried by said brackets and acting on the other side of said removable sealing frame near the outer periphery thereof for applying said jointing metallic seal against said sealing surface of said stationary frame, a gasket formed by a simple cord of heat-resistant material between said rigid removable sealing frame and a surface of said door disposed parallel to the adjacent surface of the sealing frame substantially along the inner peripheral

edge of the latter, and clamping means carried by the door and including edge portions acting on the opposite surface of said removable rigid sealing frame adjacent the inner periphery of the latter to apply said sealing frame and gasket against the door.

6. In combination with a coke oven door, a stationary metal door frame provided with an outer plane sealing surface surrounding the opening in said frame, a removable, transversely rigid, sealing frame, said removable frame being provided, on its side facing said sealing surface of said stationary door frame, with a jointing metallic seal having a half-rounded shape, brackets rigidly secured to the door, means carried by said brackets and acting on the other side of said removable frame near the outer periphery thereof for applying said jointing metallic seal against said sealing surface of said stationary frame, a projecting peripheral flange on said door, a gasket between said peripheral flange of the door and said removable rigid sealing frame, substantially along the inner peripheral edge of the latter, said gasket having a curved surface in contact with the adjacent surface of said sealing frame, and clamping means acting on said removable rigid sealing frame and carried by the door to apply said sealing frame and gasket against the door, said clamping means comprising bolts passing through said peripheral flange of the door and clamps mounted on said bolts and having edge portions acting on the other surface of said removable rigid sealing frame adjacent the inner periphery of the latter.

7. In combination with a coke oven door, a stationary metal door frame provided with an outer plane sealing surface surrounding the opening in said frame, a removable rigid sealing frame, said removable frame being provided, on its face situated opposite said sealing surface of said stationary door frame, with a jointing metallic seal having a half-rounded shape, brackets rigidly secured to the door, means carried by said brackets and acting on the periphery of said removable frame for applying said jointing metallic seal against said sealing surface of said stationary frame, a joint formed of a simple cord of heat-resistant material between a projection of the door and said removable rigid frame, substantially along the lateral edge of the latter, situated towards the door, and means acting on said removable frame and carried by the door to apply said joint against the door, the said joint cooperating with said rigid sealing frame so as to form an articulation whereby the latter, notwithstanding its rigidly, is adapted to rock on its door side whilst said half-rounded metallic seal is kept in contact with said stationary frame.
